(57) **CLAIM**

The ornamental design for a travel razor, as shown and described.

DESCRIPTION

FIG. 1 is an isometric view of a travel razor of the present invention, showing my new design;

FIG. 2 is an isometric view of the travel razor of the present invention, showing my new design;

FIG. 3 is an isometric view of the travel razor of the present invention, showing my new design;

FIG. 4 is an isometric view of the travel razor of the present invention with the cap off, showing my new design;

FIG. 5 is an isometric view of the travel razor of the present invention with the cap off, showing my new design;

FIG. 6 is an isometric view of the travel razor of the present invention with the cap off, showing my new design;

FIG. 7 is an isometric view of the travel razor of the present invention with the cap off, showing my new design;

FIG. 8 is a front view of the travel razor of the present invention, showing my new design;

FIG. 9 is a back view of the travel razor of the present invention, showing my new design;

FIG. 10 is a top view of the travel razor of the present invention, showing my new design;

FIG. 11 is a bottom view of the travel razor of the present invention, showing my new design;

FIG. 12 is a right side view of the travel razor of the present invention, showing my new design; and,

FIG. 13 is a left side view of the travel razor of the present invention, showing my new design.

The broken lines in FIGS. 5-7 illustrate portions of the travel razor and form no part of the claimed design.
